UNITED STATES PATENT OFFICE

GEORGE P. IGLEHEART, OF BOONTON, AND ALFRED L. ROSENMUND, OF ROCKAWAY, NEW JERSEY, ASSIGNEES TO STAPLING MACHINES CO., A CORPORATION OF DELAWARE

BOX AND CRATE

Application filed July 10, 1929. Serial No. 377,095.

This invention relates to boxes and box blanks and particularly to sectional wirebound boxes and box blanks.

Among other objects, the invention is intended to provide an improved cleat construction for boxes which will strengthen the box against relative shifting of adjacent sections of the box.

Other objects will be in part obvious and in part hereinafter pointed out.

One illustrative embodiment of the invention is shown in the accompanying drawings in which:

Fig. 1 is a perspective view of an open top wirebound box embodying the invention.

Fig. 2 is a top plan view on a smaller scale of a box blank which, when folded, forms the four sides of the box of Fig. 1.

Fig. 3 is a side elevation of the box blank of Fig. 2.

Fig. 4 is an end elevation of the box blank of Fig. 2.

Fig. 5 is an enlarged top plan view of one corner of the box of Fig. 1.

Fig. 6 is a side elevation of the same corner viewed from the left in Fig. 5.

Fig. 7 is a side elevation of the same corner viewed from the bottom in Fig. 5.

The box selected for illustration is of the sectional wirebound type having an interior cleat frame at the bottom of the box and an exterior cleat frame at the top of the box to provide a wirebound box having a smooth interior surface free from projections.

As shown in Fig. 1, the illustrative box comprises four separate side sections each consisting of a sheet or sheets of side material 1, an interior cleat 2 secured to the side material along its lower edge, and an exterior cleat 3 secured to the side material along its upper edge; the several sections being connected and held together by encircling binders 4 stabled to the sections. A bottom section (not shown) may be supported by or secured to the interior cleats 2, and a cover section (not shown) may be applied and secured to one or more of the exterior cleats 3.

The materials for the four side sections are usually assembled on a box blank ma-

chine and secured together in the flat, producing the box blank shown in Figs. 2, 3 and 4, which blank is then folded into box form. The side material, interior cleats and exterior cleats must be so related in the flat as to permit folding the flat blank into the box form, and are preferably related so that, when folded, the adjacent edges of the side material will overlap and the binders will be tensioned over the box corners. To accomplish such results, it has been the practice heretofore to employ exterior cleats which terminate flush with or short of the edges of the side material. Such exterior cleats, however, do not overlap at the box corners and, as a result, the side sections at the top of the box frequently shift inwardly under strain.

To prevent such inward shifting of the side sections at the top of the box, exterior cleats 3 in the present invention are so formed and dimensioned that they may be readily folded from the flat into box form, and, when folded, will overlap at the box corners. As shown in the drawings, the ends of the exterior cleats 3 are cut diagonally as at 5; the cuts at each end being parallel, and the angle of the cut preferably being such that the horizontal projection of the diagonal cut is substantially equal to twice the thickness of the cleat. The length of the exterior cleats 3 is preferably such that the center of each diagonal cut coincides with an edge of the side material, so that a portion of the cleat extends beyond each edge of the side material a distance substantially equal to the thickness of the cleat. Thus, when the exterior cleats are folded from the flat into box form, adjacent ends of the exterior cleats will overlap and portions thereof will contact and thereby resist any tendency of the side sections to shift inwardly at the top of the box.

To facilitate the folding of the blank and to resist any tendency of adjacent sections to shift vertically, grooves 5 may be cut in the ends of exterior cleats 3, in which grooves the binder 4 may be lodged under tension.

Among other advantages, the invention provides an exterior cleat construction for sectional wirebound box blanks which may be readily folded into box form and which,

when folded, provides overlapping and contacting exterior cleat ends to resist any tendency of adjacent side sections to shift relatively.

It will be understood that the invention is not to be limited to the particular embodiment thereof shown herein for illustration and that all of the features of the invention need not be used conjointly, as the invention may be variously embodied and features thereof may be used in different combinations and sub-combinations as defined in the subjoined claims.

The word "box", as used in the specification and claims is intended to include crates.

I claim:

1. A foldable box blank comprising a plurality of sections of side material connected with flexible binders and positioned to tension the binders when the blank is folded into box form, and an exterior cleat secured to each section of side material; the cleats of the several sections being in line with each other and the ends of said cleats being cut diagonally to the lateral edges of the section of side material and extending beyond the lateral edges of the side material.

2. A wirebound box comprising in combination a plurality of sections of side material connected by flexible binders secured thereto, and an exterior cleat secured to and extending beyond the lateral edges of each section of side material; the cleats of the several sections being in the same horizontal plane and the ends of the cleats being cut diagonally to the perpendicular of the box corner, whereby portions of adjacent cleat ends are in overlapping relationship.

3. An exterior cleat construction for foldable box blanks comprising an exterior cleat secured to each of a plurality of adjacent sections of the blank, the several cleats being in line with each other and having substantially parallel ends cut at an angle of substantially 45° to the perpendicular of the cleat side, and each cleat extending beyond either edge of its section a distance substantially equal to the thickness of the cleat, whereby when the blank is folded into box form, portions of adjacent cleat ends will overlap and contact.

4. A foldable box blank comprising a plurality of sections of side material connected with flexible binders secured thereto, and an exterior cleat secured to each of said sections; the cleats being in line with each other, and the ends of the cleats being cut diagonally to the lateral edge lines of the section of side material and extending beyond the lateral edges of the side material.

5. A foldable box blank comprising a plurality of sections of side material connected with flexible binders secured thereto, and an exterior cleat secured to each of said sections; the cleats being in line with each other, and the ends of the cleats being cut parallel to

each other and diagonally to the perpendicular of the cleat sides and extending beyond the edges of the side material.

6. A wirebound foldable box blank comprising a plurality of sections of side material spaced apart a distance substantially equal to the thickness of the side material; binding wire secured to and connecting the several sections; and an exterior cleat secured to each section and extending beyond the lateral edges of the section a distance substantially equal to the thickness of the cleat; the several cleats being in line and having their ends cut diagonally to the line of the lateral edges of the sections of side material whereby portions of adjacent cleat ends overlap in the flat blank and when the blank is folded into box form.

7. A wirebound foldable box blank comprising a plurality of sections of side material spaced apart a distance substantially equal to the thickness of the side material; binding wire secured to and connecting the several sections; and an exterior cleat secured to each section and extending beyond the lateral edges of the section a distance substantially equal to the thickness of the cleat; the several cleats having diagonally cut ends in overlapping relationship.

8. A wirebound foldable box blank comprising a plurality of separate sections of side material connected together by flexible binders secured thereto; and a separate cleat secured to each section, the cleats of the several sections being in line with each other and having diagonally cut ends overlapping each other.

In testimony whereof, we have signed our names to this specification this 8th day of July, 1929.

GEORGE P. IGLEHEART.
ALFRED L. ROSEN MUND.
